UNITED STATES PATENT OFFICE.

ELBERT C. HOOVER AND IRWIN C. HOOVER, OF WASHINGTON, DISTRICT OF COLUMBIA.

RACKET CASE.

Application filed September 17, 1924. Serial No. 738,215.

Our invention relates to improvements in protective cases for tennis rackets and similar stringed game bats.

Heretofore, covers for stringed game bats 5 have been used consisting of either a bulky casing for covering the entire bat head and handle or an envelope for covering only the stringed head, this latter type of case being provided with snap fasteners or strings for 10 holding the casing in position over the head.

One object of our invention is to provide for a novel and improved construction of cases for protecting the head, frame and strings of a racket or game bat.

15 Another object is to provide a case into which the portions of the racket to be protected may be easily inserted or withdrawn and which, when positioned, will effectively and instantaneously close itself around the 20 handle of the bat to keep out dirt and moisture.

A further object of our invention is to provide a racket case composed of a transparent, waterproof material so that the 25 strings of the racket or bat may be examined through the material, without removing the racket or bat from the case. In the cases as now made, it is necessary to remove the racket or bat from its case for examination.

30 In the drawings:—

Fig. 1 is a plan view of our case positioned over the racket head.

Fig. 2 is a diagrammatical showing of our case in opened position for insertion or withdrawal of the racket head.

Fig. 3 is a section taken on line 3—3 of Fig. 2, and

Fig. 4 is a section taken on line 4—4 of Fig. 2.

40 In the drawings 1 illustrates our case as an entirety, which is made of two flat sections 2 and 3, of properly shaped material, sewed together to form an open ended bag.

The method of securing together the sections of material 2 and 3 is illustrated in 45 Fig. 4. Over the edges of the material is placed the reinforcing tape 4, and the four thicknesses of fabric are sewed together as at 5. The open ended bag is then pulled in 50 side out so that the tape 4 lies within the bag and is thus hidden from view. This tape 4 is left longer than the sides of the bag for a purpose to be later described.

The bottom edge of the open end or mouth

of the bag thus formed, is folded over and in, 55 as shown in Fig. 3. An endless elastic band 8 of proper size, is placed within the fold formed by the turned in edge, and the fold sewed all around at 6, through a reinforcing tape 7 to the sides of the bag or case.

60 It will be seen from Fig. 3 that the reinforcing tape 4 is extended for a short distance below the mouth of the bag. These extensions are for the purpose of forming 65 hand pulls or tabs 9, 9, which are grapsed by the fingers of each hand and extended sideways for opening the mouth of the bag against the resiliency of the elastic band 8. This band 8 is of such a size as to normally 70 contract the mouth of the bag or case.

The ends of the tape 4 are folded over the 75 sides of the bag and sewed thereto by the stitching 6. The extensions of the tape 4, denoted 9, 9, also fold upon themselves and are again sewed to themselves and to the side walls of the bag or casing at 10. This stitching 10 is for the purpose of reinforcing and to keep the strain, when the tabs 9, 9, are pulled, from the side walls of the bag.

In use, the hand pulls or tabs 9, 9, are extended in opposite directions to open the 80 mouth of the bag or case against the tension of the elastic band 8. When the mouth of the bag or case has been opened, the racket or bat is inserted in the case and the hand 85 pulls or tabs 9, 9, released, which allows the band 8 to contract the mouth of the case tightly around the handle of the racket or bat. Thus, the racket or bat head and its 90 strings are effectively protected from dirt and moisture.

To remove the racket from the case, the 95 pulls 9, 9, are extended as before, and the racket withdrawn. The case with its mouth in opened position for insertion or withdrawal of the racket is clearly shown in Fig. 2 of the drawing.

While any waterproof sheeting of fabric may be used for constructing our cases, we 100 prefer to use varnished silk or as it is commonly known, "oiled silk."

Having thus described our invention, what we claim as new and desire to secure by Letters Patent is:

An open mouth case of the character described consisting of two similar fabric sections secured together at their peripheral edges by an attached strip, the material of 105

the case at the mouth thereof being folded back and secured upon itself, an elastic band inserted within the folded portion to normally constrict the opening of the mouth, said mouth being capable of extension by hand pulls which are formed by extending the strip which is attached to the peripher-

ies of the fabric sections beyond the mouth of the case on each side thereof.

In testimony whereof we affix our signatures.

ELBERT C. HOOVER.
IRWIN C. HOOVER.
